UNITED STATES PATENT OFFICE.

SAMUEL L. PHILLIPS AND GEORGE G. TILDEN, OF WASHINGTON, DISTRICT OF COLUMBIA.

COIN-CONTROLLED ELECTRIC METER.

SPECIFICATION forming part of Letters Patent No. 626,298, dated June 6, 1899.

Application filed January 20, 1899. Serial No. 702,778. (No model.)

To all whom it may concern:

Be it known that we, SAMUEL L. PHILLIPS and GEORGE G. TILDEN, citizens of the United States, residing at Washington, in the District of Columbia, have invented certain new and useful Improvements in Coin-Controlled Electric Meters, of which the following is a specification.

The following are purposes of this invention: first, to provide a prepayment electric meter in which no electromagnets are used and no electric circuit is established by contact of the inserted coin; second, to wholly avoid the employment of clock-gearing or any mechanism in which power is stored up by the periodic winding of a spring, weight, or any other means for producing a like result; third, to throw no load upon the wattmeter at any time; fourth, to render the meter automatic in every particular, no act being required from the customer, except to deposit the proper coin in the slot; fifth, to enable the consumer to ascertain at any moment during the period the meter is registering how much current is still coming to him, or, in other words, what part of the whole amount he has paid for is at that moment unconsumed, simple automatic means being used to notify him that the supply will cease within a certain number of minutes unless a further payment be made; sixth, to enable the consumer to pay in either a single coin or any number of coins, one after another, not to exceed a given sum and to control the wattmeter thereby in such manner that the full amount of current represented by the single payment or by the sum of the several payments shall be supplied without any break or interruption and without the possibility of any loss being suffered either by the consumer or by the generating company; seventh, to enable the consumer to make an additional payment at any moment he may choose during the period that current is being supplied and to permit such additional payment to consist of a single coin or of a number of coins introduced consecutively, or to so control the wattmeter that it shall continue to register until the residue of current due the consumer at the moment when the additional payment is made plus

the full amount of current represented by the coin or coins constituting the additional payment shall have been furnished and consumed; eighth, to enable the customer to use not only one denomination of coin, but several, as may be convenient to him; ninth, to prevent money which has been introduced from being abstracted, and, tenth, to prevent the mechanism from being successfully operated by any contrivance except coins.

The invention also aims to provide a prepayment apparatus which may be used with any meter either as an attachment thereto or as a constituent part, and in this connection it is a further object to provide a prepayment-meter capable of being used either with or without the registering-dials of the ordinary recording-wattmeter, the main function of such dials when present being to record the total current consumed during each week, month, or other period, and thereby ascertain whether the sum of the individual payments corresponds with the aggregate of the watts or of the kilo watt-hours registered, thus affording to the generating company a convenient and accurate method of detecting surreptitious removals of coin deposited or any other attempt by a consumer or other person to defraud it of its proper revenue and serving also to detect any defects in the meter by which accuracy of registration is impaired.

The invention possesses other useful and novel features, all of which will be fully described in the following description and then particularly pointed out and defined in the claims.

For the purposes of this description reference will be had to the accompanying drawings, in which—

Figure 1 is an elevation of the interior of an electric meter having our invention incorporated. Fig. 2 is a plan view of the same. Fig. 3 is a detail view of the dial and coin-operated mechanism of the prepayment attachment. Fig. 4 is a detail view showing the dial and pawl-and-ratchet devices. Fig. 5 is a detail section on the line 5-5 in Fig. 4, showing a modified form of the dial mechanism. Fig. 6 is a detail view of the dial and sight-opening. Fig. 7 is a diagram of the cir-

cuits, the mechanical parts appearing in said figure being shown merely in the order in which they stand related to said circuits and without regard to their exact location in an operative sense, the cam being shown as less than its usual size. Fig. 8 is a detail section showing a modified form of coin-chute for coins of more than one denomination. Fig. 9 is a sectional view of a coin-chute for coins of more than one denomination.

The reference-numeral 1 in said drawings indicates any ordinary or known style of wattmeter and either of the continuous or alternating current, in which a motor-armature 2 imparts movement to the units-dial of a series of registering-dials 3. As these parts are of any familiar construction and as the invention hereinafter to be explained is not limited to any special type of wattmeter, they 20 are shown in the drawings conventionally only and need not be described in detail.

The wattmeter is connected in a manner suitable to the type of said meter, and in the present instance it is shown as having its field-coil connected to one side of a double-pole switch, consisting of two blades 4, pivoted in posts 5 and normally thrown by one or more springs 6 into suitable clips 7. This switch is opened by a cam 8, mounted on a shaft 9, upon which is a worm-gear 10, meshing with a worm 12 upon a shaft 13. This shaft is operated when the switch is opened by a small electromotor 15 of any suitable type and for either a continuous or alternating current. When opened to a proper point, the switch-blades are held by a hook or latch 16, which engages a lip 17 on the yoke 18, which connects the ends of the switch-blades. The hook engagement may be insured by any 40 suitable means, but the gravity of the latch will cause it to engage the lip 17. It is tripped or disengaged by a coin-lever 20, which is fulcrumed on a shaft 21, the latter also having a support for the hook 16. The coin-lever 20 extends from said shaft into the path of the 45 coins, which are inserted in a slot 22 and pass by gravity through a chute 23 and thence into any suitable receptacle 24. The unattached end of the coin-lever 20 moves in the 50 arc of a circle which intersects the line of movement of the coin, and it moves with the coin for a certain distance and then withdraws entirely from its line of movement, leaving the coin to follow the chute 23 and pass into the receptacle 24. The coin-lever 20 is returned to its normal position of rest 55 by any suitable means, such as an adjustable counterbalance 25.

Upon the shaft 21 is a rigid arm 26, which 60 is coupled by a light connecting-rod 27 to an arm 28, which forms part of a pawl 29. This pawl is pivoted upon a pawl-lever 30, which is sleeved upon a shaft 31 in such manner that it can turn freely thereon with but little 65 friction and without in any manner affecting the functions of said shaft, which is preferably supported in cone-bearings 32, as shown,

though any other construction that is suited to the object in view may be adopted in place of that shown.

Upon the shaft 31 is a disk 33 of any suitable diameter and mounted in such a manner as to be capable of turning upon the shaft in one direction and with said shaft in the opposite direction. To produce the movement 75 upon the shaft, the disk is provided with a concentric ratchet 34, rigid with one of its flat faces, and with this ratchet the pawl 29 engages, carrying the ratchet with it when the pawl-lever 30 swings downward, but having 80 no contact with the ratchet-teeth when the pawl-lever rises to its normal position of rest. This alternate engagement with and disengagement from the teeth of the ratchet is due to the fact that the weight of the pawl-lever 85 and pawl is very nearly if not quite balanced upon the other side of the shaft 31 by the action of the counterbalance 25 upon the pawl-lever through the connecting-rod 27. The weight of this counterbalance is such as to 90 enable it to have the required action upon the coin-lever 20 as well as upon the pawl-lever 30. To secure the exact degree of counterbalance needed, the weight 25 is threaded upon an arm 25^a, projecting from the shaft 95 21. It is desirable that the weight should not only raise both the coin-lever and the pawl-lever back to their normal positions of rest, but that it shall also make it necessary for the rod 27 upon its downward movement to 100 exert a sufficient downward pull upon the arm 28 to throw the pawl 29 into the teeth of the ratchet 34. This result may also be produced by the resistance of the pawl-lever 30 in turning on the shaft 31, and a very slight friction 105 upon the sleeve of the pawl-lever will cause the connecting-rod 27 to exert a sufficient downward pull upon the end of the pawl-arm 28 to instantly throw its point into the teeth, the movement required to effect this being 110 very small. In like manner the upward thrust of the connecting-rod 27, caused by the rise of the arm 26, throws the point of the pawl just clear of the teeth of the ratchet and restores it to its position, while at the same 115 time it maintains this clearance from the ratchet. In this manner a large part of the wear and tear on the ratchet and pawl is avoided, and the pawl is prevented from arresting the revolution of the disk when the 120 latter is turning in unison with the shaft 31.

A worm-gear 35, rigid on the shaft 31, meshes with a worm 36 on a shaft 37, which receives movement from a worm 38^a on the shaft of the armature 2, which worm 38^a 125 meshes with a worm-gear 38, rigidly mounted on the aforesaid shaft 37.

The wiring of the meter shown in Fig. 7 is as follows: The service-wires 40 and 41 are brought in as usual, one going to the field-coils of the wattmeter and thence to the post 5, supporting one blade of the knife-switch, while the other goes directly to the other post 5^a. The armature is supplied by a shunt 42,

as in the well-known Thompson recording-wattmeter. A wire 43 is also tapped off the service-wire 40 and taken to one brush of the small motor 15, and from the other brush a wire 43^a goes to a contact-spring 44, placed in suitable proximity to the dial 33. A wire 45 is tapped off the service-wire 41 and then to the cam 8 or to the shaft 9, which carries said cam. A wire 46 is tapped off a contact-plate 47 on the yoke 18, so placed thereon that the cam 8 shall abut against it in opening the switch and abut against said contact-plate with its edge when the switch-blades 4 are in the clips 7. The wire 46 is taken to the disk 33 or the shaft 31, on which said disk is mounted. A contact-pin 48, projecting from the dial 33, is brought lightly into contact with the spring 44 as often as the disk revolves in unison with its shaft 31 far enough to effect this engagement. The house-wires 49 49^a are connected to the clips 7 and 7^a of the knife-switch.

The dial 33 is calibrated or divided into a number of equal sectors, Fig. 6, each representing the exact distance through which said dial is moved at each downward swing of the pawl-lever 30. This movement can be very accurately spaced by adjusting the end of the connecting-rod 27 upon the lever-arm 26. Moreover, the length of the coin-lever 20, the angle at which it intersects the chute 23, the distance that the said coin-lever extends into or across the coin-chute, and the consequent length of the arc through which it moves before its extremity withdraws from the line of movement of the coin are all factors in determining the fractional revolution of the dial 33. The calibration of the latter is such that each one of the equal divisions represents in the revolution of the dial as produced by the worm 36, which is driven by the armature of the wattmeter, a supply of current that corresponds with a single-coin payment.

The operation is, briefly, as follows: In its normal position of rest the contact 48 on the dial 33 is resting on or against the spring-contact 44, as seen in Fig. 3. Let it be assumed that the unit payment is a silver half-dollar, although a coin of any other denomination may be used, if preferred, provided the chute 23 be of such dimensions as to let the coin pass freely, but prevent excessive lateral deflection. For convenience of illustration radial lines are placed on the disk 33 to mark the equal sectors or divisions, and these lines are distinguished one from another in any suitable manner—as, for instance, by placing a cipher or zero on the line coinciding with the contact 48 and placing toward the right hand the numerals “1,” “2,” “3,” *et seq.* in their proper order. Any other symbols may be used instead of numerals, the latter being preferred merely for the purposes of this description.

Let us now suppose that a single coin is placed in the slot 22. It passes by its own gravity down the chute 23, impinges upon

the end of the coin-lever 20, which intersects its path, carries said lever through an arc denoted by dotted lines, and, its functions being thereby performed, it drops into the box 24, placed to receive it. The coin-lever 20 in its downward swing causes a short stud 20^a, projecting from one of its flat faces, to bear upon a projecting part of the latch 16, which sustains the switch-blades in their raised position. By this movement the coin-lever 20 trips the latch 16, which releases the switch-blades 4, and they are snapped into the clips 7, thereby establishing the circuit of the wattmeter and of the house-wires. If the consumer's main-line switch is closed, his lamps will be instantly lighted. By the same downward swing of the coin-lever 20 the pawl-arm 28 is drawn downward, thereby pressing the nose of the pawl 29 into the teeth of the ratchet 34. The pull of the coin-lever now carries the pawl-arm 28 and the pawl-lever 30 downward in unison with the coin-lever 20, and by this movement the ratchet 34, being carried by the pawl, turns the dial 33 through a part of a revolution, which is measured by the arc of its circumference intercepted by the first and second radial lines of division—that is, by the lines denoted by a zero and the numeral 1, respectively. This position is shown in the detail view in Fig. 6. The coin at this point passes off the end of the coin-lever 20, and the latter being released it rises to its normal position of rest by the action of the counterbalance 25. The instant that its upward movement begins the thrust of the connecting-rod 27 draws the point of the pawl 29 out of the teeth of the ratchet 34 and carries the pawl-arm 28 and pawl-carrier 30 back to the position they occupied before the coin was dropped in. This restoring movement does not affect either the shaft 31 or the dial 33, since the pawl has complete clearance of the teeth of the ratchet during said movement, and the pawl-carrier 30 is sleeved upon the shaft 31 and turns thereon without perceptible friction. The instant that the meter begins to register the worm 38^a on its armature-shaft acts upon the worm-gear 38 and slowly revolves the shaft 37. The worm 36 on this shaft imparts revolution to the worm-gear 35, which, being rigidly fixed upon the shaft 31, causes the latter to turn with it, thereby causing the dial 33 to move in unison with the shaft 31. The direction of this rotation is indicated in Fig. 3 by an arrow placed upon the worm-gear 35. It will be observed that the pawl 29 turns the dial in one direction, (shown by an arrow upon the ratchet 34,) while the worm 36 revolves it in the opposite direction. By the insertion of the coin the division-line on the dial bearing the zero-mark and which was lying in line with a pointer A, which indicates the starting-point, has been moved from the right hand toward the left in Figs. 2 and 3, the extent of this movement being just sufficient to bring the next radial line (marked 1) into line with the

pointer A. The meter being now in an established circuit, the consumption of current will be registered by the dials of the wattmeter and measured by the calibrated dial 33 of the pre-payment attachment. The movement of the dial 33 in performing this function is from the left hand toward the right in Figs. 2 and 3, and the moment the full supply of current paid for by the inserted coin or coins has been consumed the pin-contact 48 on the dial 33 impinges upon the spring-contact 44, thereby completing a circuit from the negative service-wires 41 over the wire 45, shaft 9, and cam 8, from the shaft 9 and cam 8 to the plate 47 on the yoke of the knife-switch, (said plate being in contact with the edge of the cam 9 when the switch-blades 4 are in the clips 7 and 7^a,) from said plate by the wire 46 to the shaft 31 or dial 33, from said shaft and dial 20 by way of the pin 48, contact 44, and wire 43^a to one brush of the small motor 15, and from the other brush by a wire 43 to the positive service-wire 40. The motor 15, which is quite small, being practically no more than a very diminutive toy motor, starts upon the completion of the circuit described and the cam 8 is turned through a complete revolution, and it lifts the blades 4 of the knife-switch, separating them from the clips 7 and 7^a, opening the 25 circuit of the wattmeter and the house-circuit. The latch 16 snaps under the lip 17 and retains the blades 4 in their raised position, in which the spring or springs 6 are under sufficient tension to force the blades into the clips when the circuit is again closed by the 30 insertion of another coin. The cam 8 in completing its revolution passes off the contact-plate 47 and opens the circuit of the motor 15, which stops, leaving the parts substantially in the position shown in Fig. 2. It should be noted that the circuit of the motor 15 is completed by the movement of the dial 33, which brings the contacts 44 and 48 together and leaves them in electrical contact 35 when the dial is at rest. Said circuit is opened when the work of the motor is finished by the cam 8 passing off the contact-plate 47 on the yoke 18 of the double-pole knife-switch. No sparking can occur therefore between the 40 two contacts 44 and 48, which remain in touch until the introduction of a coin, when they are separated by the fractional revolution of the dial.

If the consumer desires to purchase more current than the quantity represented by a single coin, he can pay in as many half-dollars as he thinks proper, provided that the number of inserted coins be equal to the number of divisions upon the dial 33. In the present 45 instance twelve of these divisions are shown, so that eleven coins may be paid in one after another. This will carry the dial around not far short of a single revolution. The circuit of the wattmeter being established by the passage of the first coin, registration goes on during the insertion of the others, and if the operation is performed deliberately and a con-

siderable number of translating devices are in operation the dial 33 may have time to turn with the shaft 31 through a distance 70 equal to part of the arc intercepted between the zero radial line and the one next succeeding toward the right.

To illustrate the advantages of the dial 33 or its equivalent, it should be noted that in 75 paying in any number of coins—as, for example, six—when interruptions prevent their consecutive insertion in the coin-slot with ordinary rapidity the prepayment apparatus will protect both the consumer and the generating company from any loss. For example, let us suppose that the consumer has paid in two silver half-dollars, one following the other so closely that the brief interval may be disregarded. These two coins have given 80 the dial 33 two consecutive fractional movements, whereby the line on the dial corresponding with the numeral 2 is brought to the pointer A, showing that two coins, or one dollar in all, has been paid in. In correspondence with this amount the measuring-dial 33 has been turned back, or toward the left in Fig. 1, its movement covering two equal fifty-cent spaces, and in measuring off the consumption of the current the wattmeter 85 by giving rotary movement in the opposite direction to the dial will bring the contact-pin 48 back to its normal position of rest in touch with the spring-contact 44. The current purchased having then been supplied 90 and consumed, the motor 15 will open the switch and cut off the supply.

We will suppose that after inserting the second coin the consumer is called away and is absent so long that eighty-nine cents of his 105 payment has been extinguished by the amount of energy furnished and used, leaving a residue still due him that represents the unextinguished balance of eleven cents required to make the dollar paid in.

At this point the consumer pays in his third coin or third half-dollar. As the movements of the coin-lever 20, and consequently of the dial 33, are equal each to another, it is evident that the dial will be carried back, or to 115 the left in Fig. 1, over the space which its revolution with the shaft 31 has just measured. This space represents a consumption of fifty-cents' worth of energy, and when the third coin passes into the meter the dial is 120 set back by a fraction of a revolution exactly equal to a fifty-cent space and the dial must move forward, or toward the right in Fig. 1, a space equal to said fifty-cent space, by which distance it has been set back, and must 125 also move forward a further space equal to that which it still had to traverse when the third coin was put in. By the action of the latter coin, therefore, the dial 33 will be set to such a point that it must measure an aggregate of sixty-one cents' worth of energy 130 before it arrives at the point where its pin-contact 48 can engage the spring-contact 44 and complete the circuit of the motor 15, by

which the switch is opened and the supply of current cut off. The operation of the parts is the same as if one or more coins are dropped at any time during the period that the watt-meter is registering or as long as there remains any residue of energy that is not consumed. Under no circumstances can the consumer lose a cent's value in energy nor can the generating company suffer even the smallest loss.

One of the flat faces of the dial 33 is provided with suitable characters or symbols spaced at convenient and equal intervals and exposed by means of a sight-opening 52 to the eye of a person standing near the meter. These characters are so chosen that they give to the consumer or other person having charge of the meter intelligible information as to what residue of energy is still unconsumed. For example, said characters may be numerals denoting the watt-hours or kilo watt-hours, measured by the dial movement, or they may express the value in cents or in fractional parts of a dollar or half-dollar. Such numerals, therefore, will be successively less, taking them in a direction opposite to the direction of revolution of the dial 33, when it moves in unison with the shaft 31. By looking into the sight-opening 52 the consumer can at any moment roughly estimate the period during which current will be supplied in return for the coin payment already made. He need not therefore wait until the automatic signal informs him of the close approach of the moment when the supply will be cut off, unless a further payment of one or more coins be made. If he is to be absent and has no person in whose charge he can leave the meter, he will be able to calculate approximately how many coins he should drop in before he goes away in order to insure a supply of energy which will continue until he returns. The additional payment, whether it consists of one or of a number of coins, he can make at any moment, even at the instant the signal is made or after said signal, and at any moment up to the time when the contact-pin 48 is almost in touch with the contact-spring 44. The first coin then dropped in sets the dial 33 back instantly a single space or distance, and each succeeding coin does the same. The period of supply and consumption can be extended or prolonged in this manner without the slightest break or interruption in the current.

The coin-chute is shown in detail in Fig. 3, with the end of the coin-lever 20 lying in place therein ready for the descent of the coin. In order to prevent or frustrate the fraudulent attempts made in this class of apparatus to obtain current by inserting a strip of metal that will operate the coin-lever or by dropping in a genuine coin or a dummy with a string or wire secured to it by which it may be drawn out after its function is accomplished, the following provisions are made: The chute is divided into two parts, one of

which has a gentle downward inclination from the slot where the coin is introduced to the point where it meets the second part, which is preferably vertical, or nearly so, though we need only a sufficient inclination to insure the proper descent of the coin. At or near the point where the two parts of the chute meet the lower end of the first portion is curved laterally and downwardly, each curve having a suitably short radius. Both parts are covered, but the top plate 23^a of the first part is cut away at the curve in such manner as to wholly remove everything that would act as a guide in the introduction of a metallic, elastic, or flexible strip the passage of which from the first part into the second or vertical part would be practically impossible.

To guard against the insertion of a coin or a dummy and its withdrawal by a string after operating the coin-lever, a trap is placed in the second part of the chute, consisting of a series of teeth rigidly mounted on a rock-shaft 58, which lies just outside and across the line of the chute. The teeth 59 normally lie in the chute and across the latter, making a small angle with the line of movement of the coin, which readily pushes them back in the slots through which said teeth project, so that the coin passes without impediment. The moment it has passed the teeth swing in again and lie in such position that the attempt to draw up the coin by the attached cord or wire will merely hold them more rigidly across the chute. By converging and sharpening their adjacent edges they can be made to sever the cord or wire with but a slight tension on the same. Thus if the consumer drops in a half-dollar with a cord attached he will loose it, but will receive its equivalent in energy. If he uses a counterfeit or dummy, it will be found in the drawer, and proper steps can then be taken by the generating company to punish the fraud.

It is one of the objects of this invention to so organize the prepayment devices that no act or services of any kind shall be required of the consumer except to drop one or more coins in the coin-slot of a denomination corresponding with the unit payment. We aim to wholly do away with cranks, levers, push-bars, outside handles, and all the other paraphernalia which have so frequently been used in prepayment-meters for both gas and electricity and which the consumer must operate in accordance with specific instructions whenever he puts in a coin. It is also our purpose to dispense with electromagnets and not to use the coin as part of an electric circuit or circuits. All that we require of the coin is that it shall move the coin-lever 20 by its momentum as it drops down the coin-chute. As this lever is quite small and very light and as its sole functions are to trip the latch 16 and to transmit motion to the pawl-lever 28, even a light coin will have sufficient momentum to insure the action of said lever. The coin passes with a continuous

uninterrupted movement from the point of its insertion in the meter to the receptacle 24 prepared for it. After passing the angle between the parts 23 and 23^a of the chute the 5 coin preferably goes to the receptacle 24 by the shortest path, so that the part 23 of the chute should be vertical or sufficiently so to give the coin operative effect upon the coin-lever 20, undiminished by friction and by the 10 slower movement it would have if the chute were inclined. The unattached end of the coin-lever 20 enters, in its normal position of rest, the vertical portion of the chute at a suitable distance below its upper end and stands 15 directly across the path of the coin and in the present instance at nearly a right angle to the vertical part of the chute. As it swings downward under the impact of the coin its end moves in an arc (shown in dotted lines) struck 20 from the axis of the shaft 21. If this arc be slightly prolonged until it meets the chute above the end of the coin-lever 20, said chute will occupy the position of a chord subtending said arc, and at the lower point of intersection the end of the coin-lever will pass 25 entirely out of the coin-chute and will cease, therefore, to be affected by said coin. The stroke of the coin-lever 20 ends, therefore, at this point, and while the coin drops from the 30 chute into the receptacle 24 the lever returns to its normal position of rest. (Shown in full lines in Fig. 1.) By the arrangement described the successive strokes of the coin-lever will always be exactly equal one to another, and 35 thus the proper discharge of its functions will be assured.

By a modified form of the coin-chute, Figs. 8 and 9, it is possible to use coins of more than one denomination in order to make the 40 necessary prepayment without in any respect changing the other parts. For example, to adapt the meter to the use of a silver half-dollar and a silver dollar, either or both to be used as circumstances may render convenient, it is only necessary to combine with the coin-chute for the half-dollar a separate chute of such size as to receive the silver dollar, the latter chute being extended beyond the point at which the coin-lever 20 completes 45 its stroke under the action of the half-dollar. This prolongation is such that the end of the coin-lever after leaving the half-dollar chute 23 at the point where the fifty-cent stroke of said coin-lever is completed 50 will remain in the dollar-chute 23^b long enough to enable it to complete a further movement equal in extent to that produced by the half-dollar, thereby carrying the dial 33 forward over a space equal to two of the divisions on 55 its face or corresponding to one dollar. To accomplish this, the dollar-chute 23^b is curved below the point where the fifty-cent stroke of the lever 20 is completed, the curve being in an arc struck from a point eccentric to the 60 pivotal axis of the coin-lever. In this manner provision can easily be made for the use of coins of several different denominations 65

without any change except such addition to the coin-chute as is required to guide said coins and preserve the engagement of each 70 with the end of the coin-lever long enough to produce a stroke of the latter that will carry the dial forward a space corresponding to the value of the coin introduced. Each coin will only be operative when introduced 75 in its own chute.

A modified form of the dial apparatus heretofore described is shown in Fig. 5, in which the dial, instead of advancing by intermittent movements as the several coins 80 are paid in and then moving under the control of the metering mechanism back to its normal point of rest, will move continuously though intermittently forward or in the same direction, and at each of its successive points 85 of arrest it will await the overtaking movement of a contact upon a moving part either of the metering mechanism or of an element receiving its motion from said mechanism. As a single example of the many different 90 forms in which this principle may find embodiment we have shown in Fig. 5 the dial 33, mounted on its shaft 31, with its ratchet, pawl-lever, and pawl, as already explained. Upon a separate shaft 33^a, in the same line 95 with the shaft 31, is a disk 53, parallel with the dial and separated from it by a narrow space. The disk 53 carries a contact 54, which moves with the disk in a circle that coincides with the path of the contact 48 on the 100 dial 33. In this construction the dial will always move in one direction and will be acted upon by the pawl 29 only. The disk 53 will be rotated also in one direction only, so that its contact 54 will follow after, and when the 105 current paid for is consumed said contact 54 will overtake the contact 48 on the dial 33, thereby establishing the circuit of the motor and opening the switch. This overtaking movement of the disk 53 is produced by the 110 wattmeter, and the same means may be used as those that in other figures of the drawings drive the dial 33—viz., the worm 36 on the shaft 37, meshing with the worm-gear 35, which would be placed on the shaft 33^a instead of upon the shaft 31. 115

The separation of the shafts 31 and 33^a is only a convenient way of insulating the parts that carry the contacts 48 and 54. In some respects, however, this overtaking movement 120 is preferable to the forward and backward movement of the dial 33. It enables the pawl and ratchet, as well as the dial 33, to be placed wholly out of connection with the wattmeter and only imposes upon the latter the task of 125 driving the disk 53, which may be so light and so far reduced in size that the force required to revolve them will be extremely small and incapable of measurement except by the most delicate instruments. It simplifies the insulation, and if ordinary care is exercised in the construction it insures absolute accuracy in operation. It prevents the 130 use of the sight-opening 52; but this is not

a material disadvantage, as each consumer knows how many hours of consumption a given prepayment will cover, and in almost all cases the period for which light is required 5 is estimated before payment is made and the amount paid is merely enough to cover that period.

To apprise the consumer that the supply of current is about to cease unless further pre- 10 payment is made, a suitable signal 55, such as a buzzer, is arranged at any suitable point, one of its wires 56 being connected to a contact 57, so placed that the contact 48 on the dial will engage it a moment or two before 15 the latter reaches the contact 44. The other wire 58 is connected to any part of the circuit of the motor. Thus both signal and motor are operated by a single circuit which divides into two branches at the point where 20 the wire 58 is tapped off.

Having thus described our invention, what we claim as new, and desire to secure by Letters Patent of the United States, is—

1. In a prepayment electric meter, the combination with a circuit for said meter, of a spring-closed switch to make and break said circuit, a coin-operated lever having a latch to sustain the switch when open, an electric motor to open the latter, a circuit for said 25 motor completed by the action of the metering mechanism, and means operated by said motor to open the switch and to break the motor-circuit, substantially as set forth.

2. In a prepayment electric meter, the combination with a metering mechanism, and with a circuit for the same, of a self-closing switch to establish said circuit, a latch to maintain said switch in open position, a coin-operated lever to trip the latch and release the switch, 30 and a dial operatively connected to said lever and to the metering mechanism, to limit the duration of action of the latter, substantially as set forth.

3. In a prepayment electric meter, the combination with a metering mechanism and a circuit for the same, of a self-closing switch in said circuit, means for maintaining said switch in an open position, a coin-operated lever to release said switch, a dial operatively 35 connected to said lever and to the metering mechanism, a device acting directly upon the switch to withdraw it from its clips, electrically-operated means for actuating said device, and an energizing-circuit including said device and a contact on the dial, substantially as set forth.

4. In a prepayment electric meter, the combination with the meter-circuit, of a self-closing switch to open and close said circuit, 40 means for maintaining said switch in its open position, a lever operated by the passage of a coin to release the open switch, a device to open the switch when the supply of current is to cease, an electric motor to operate said 45 device, a dial deriving an equal intermittent movement from each stroke of the lever that

releases the switch, a circuit for the electric motor, and two contacts in said circuit which are normally in touch but are separated by the intermittent movement of the dial and 50 brought together again to close the motor-circuit by the action of the registering mechanism of the meter, substantially as set forth.

5. In a prepayment electric meter, the combination with the meter-circuit of an automatically-closed switch to open and close said circuit, means for maintaining said switch in its open position, a lever operated by the passage of a coin to release said switch when 55 open, a device to open the switch when the supply of current is to cease, a motor to operate said device, and a circuit for the motor which is established by the action of the metering mechanism and broken by the device acting upon the switch to open the latter, substantially as set forth.

6. In a prepayment electric meter, the combination with the circuit of the meter, of a self-closing switch, means for sustaining said switch in its open position, a coin-operated 90 lever to release said switch and permit it to close and establish the circuit, and a coin-chute in which coins of a predetermined value have continuous downward movement, the end of the coin-operated lever being arranged 95 in said chute in the path of the coin, and having a line of movement, whereby it passes out of the chute at the end of a stroke of a given length, and is removed from the path followed by the coin, substantially as set forth. 100

7. In a prepayment electric meter, the combination with the metering mechanism, of a circuit for the same, means for opening or interrupting said circuit, electrically-actuated apparatus for operating the circuit-interrupting devices, a circuit for said apparatus, a movable contact forming part of the latter circuit, a lever having one portion lying in the direct path of, and adapted to move with a coin traveling from a coin-slot to a coin-receptacle, means operated by the coin-produced movement of said lever to displace the movable contact by a fixed distance at each coin-produced movement of the lever, a second contact normally in touch with the first 115 and forming part of the same circuit, and means for bringing said contacts together by the action of the registering mechanism, substantially as set forth.

8. In a prepayment electric meter, the combination with the metering mechanism, of a circuit for the latter, a self-closing switch in said circuit, means for maintaining said switch in open position, electrically-operated devices for opening said switch, a circuit for said devices, two contacts normally in touch when the meter is idle and forming part of the circuit last named, a lever lying in the path of a coin traveling from a coin-slot to coin-receptacle, means operated by each coin-produced movement of said lever to separate said contacts by a fixed distance, and a connection 125 130

with the metering mechanism to bring said contacts together by the action of said mechanism, substantially as set forth.

9. In a prepayment electric meter, the combination with the metering mechanism and circuit, of a self-closing switch in said circuit, means for maintaining said switch in open position, electrically-operated devices for opening said switch, a circuit for said devices, two contacts normally in touch when the meter is idle and forming part of the latter circuit, a lever to release the open switch operated by the movement of a coin in traveling from the point of its introduction to a coin-receptacle, means connected to said lever to separate the contacts by a fixed distance at each coin-produced movement of the lever, and a connection with the metering mechanism to bring said contacts together by the action of said mechanism, substantially as set forth.

10. In a prepayment electric meter, the combination with the metering mechanism and circuit, of a self-closing switch in said circuit, a latch to support the switch in open position, electrically - operated devices to open said switch, a circuit for said devices, a lever to trip the latch, said lever being arranged in the path of and moving with a coin traveling continuously from the point of its introduction to a coin-receptacle, two contacts normally in touch and forming part of the circuit of the devices that open the switch, means operated by the lever to separate said contacts by a fixed distance at each coin-produced movement of the lever, and a connection to the metering mechanism to bring said contacts together by the action of said mechanism, substantially as set forth.

11. In a prepayment electric meter, the combination with the metering mechanism and circuit, of means for opening said circuit to cut off the supply of current, a dial controlling the operation of the circuit-opening devices and deriving movement from the metering mechanism, a lever operated by the movement of a coin in passing from the point of its insertion to a coin-receptacle, and means operated by said lever at each coin-produced movement to set said dial independently of the movement it derives from the metering mechanism, so that the latter movement will time the duration of the supply of current, substantially as set forth.

12. In a prepayment electric meter, the combination with a metering mechanism and circuit, of a switch to open said circuit to cut off the supply of current, an electric motor and circuit to operate the switch, two contacts, normally in touch, one with the other, when the meter is idle and forming part of said motor-circuit, one of said contacts deriving motion from the metering mechanism, a lever arranged in the path of and moving with a coin as the latter passes from its point of entrance to a coin-receptacle, and means operated by each coin-produced movement of said lever to separate said contacts, and to set one

of them at such a point, independently of the movement derived from the metering mechanism, that the latter movement in bringing 70 said contacts together again shall measure the period during which current is supplied, substantially as set forth.

13. In a prepayment electric meter, the combination with a metering mechanism and circuit, of a switch for opening said circuit, an electric motor to open said switch, a circuit for the motor, two movable contacts included in said circuit which are normally in touch when the meter is idle, one of said contacts 80 deriving movement in one direction from the registering mechanism, a coin-lever arranged in the path of a coin passing from an entrance-slot to a coin-receptacle, and means connected to said lever whereby each coin - produced 85 movement will move the other contact in the same direction that the contact first named is moved by the registering mechanism, the first coin-produced movement causing said contacts to separate and open the motor-circuit and each subsequent movement increasing the separation of said contacts by a space, the movement over which by the contact first named represents the supply of current corresponding to a single prepayment, substantially 95 as set forth.

14. In a prepayment electric meter, the combination with a metering mechanism and circuit, of a switch in said circuit, a device for opening said switch, an electric motor to operate said device, a circuit for the motor, two movable contacts, normally in touch one with the other and forming part of said motor-circuit, a lever operated by the passage of a coin from a coin - slot to a coin-receptacle, 105 means operated by said lever to separate one contact from the other, thereby opening the motor-circuit and to increase said separation at each successive coin-produced movement, and a connection with the metering mechanism 110 to move the other contact in the same direction as the first, its movement over the interval separating them measuring the period of current-supply, and the overtaking of the other contact completing the motor-circuit 115 and opening the switch in the meter-circuit, substantially as set forth.

15. In a prepayment electric meter, the combination with a metering mechanism and circuit, of a self-closing switch in said circuit, a 120 device to open said switch, an electric motor and circuit to operate said device, means for sustaining the switch in open position, two contacts in the motor - circuit normally in touch, one of said contacts deriving rotary 125 movement in one direction from the metering mechanism, a lever arranged in the path of a coin passing from a coin-slot to a coin-receptacle and means operated by the coin-produced movement of said lever to release the 130 open switch and to advance the other contact in the same direction that the first contact is moved by the metering mechanism, and in the same rotary path, whereby the latter con-

tact, upon overtaking the one advanced by the lever, again completes the circuit of the motor, said circuit being interrupted by the device opening the switch, which is included in 5 said circuit, substantially as set forth.

16. In a prepayment electric meter, the combination with a metering mechanism and circuit, of a self-closing switch in said circuit, a cam to open said switch, means for sustaining said switch in open position, an electric motor to actuate said cam, a circuit for the motor including said cam and a part on the switch against which said cam bears in opening the same, a lever to release the open switch 10 arranged in the path of a coin passing from a coin-slot to a coin-receptacle, two movable contacts, normally in touch one with the other, both being included in the motor-circuit, one of said contacts deriving rotary movement 15 from the metering mechanism, and means operated by the coin-produced movement of the lever to separate said contacts, thereby opening the motor-circuit at that point, said circuit being completed between the cam and 20 the part of the switch engaged by it, by the automatic closing of said switch, which is released by the coin-produced action of the lever, the movement of the first contact by the metering mechanism bringing it again in 25 touch with the other and establishing the motor-circuit, which is opened again after the cam has operated by said cam passing off the part on which it bears, substantially as set forth.

30 17. In a prepayment electric meter, the combination with a metering mechanism and circuit, of a device to open said circuit when the current paid for has been supplied, an electric motor and circuit to operate said device, two contacts in said motor-circuit normally in 35 touch, a coin-chute, a lever having one end lying in said chute in the path of the coin, the chute having the position of a chord subtending the arc in which the end of the lever 40 moves, whereby, upon completing a movement of predetermined extent under the impulse of the coin, the end of the lever passes out of the chute and out of the path of the coin, means operated by each coin-produced 45 movement of said lever to move one of the two contacts in the motor-circuit away from the other, and a connection with the metering mechanism whereby said contacts are again brought into touch to complete the motor-circuit and open the meter-circuit, substantially as set forth.

50 18. In a prepayment electric meter, the combination with a metering mechanism and circuit, of electrically-operated devices for opening said circuit, a circuit for said devices, a movable dial to control the time of operation of said devices, a coin-chute to guide the coins paid in, a lever having one end lying in said chute in the path of the coins traversing 55 the latter, means operated by each coin-produced movement of said lever to set the dial,

and a connection with the metering mechanism whereby said dial shall complete the circuit of the devices opening the meter-circuit, the end of the coin-operated lever moving in 7c an arc of a circle and the chute lying in the line of the chord subtending said arc, substantially as set forth.

19. In a prepayment electric meter, the combination with a metering mechanism and circuit, of a self-closing switch in said circuit, devices for opening said switch, means for sustaining the latter in open position, an electric motor and circuit to operate the switch-opening devices, two contacts normally in touch 75 and forming part of the motor-circuit, a coin-chute to guide coins paid in from a slot to a receptacle, a lever having one end entering the chute and lying in the path of the coin traversing the latter, said end moving under 80 the impulse of the coin in a line diverging from the line of the chute and passing out of the latter after completing a movement of the required extent, means operated by each coin-produced movement of said lever to separate 85 the contacts in the motor-circuit, and a connection with the metering mechanism to bring said contacts together again, substantially as set forth.

90 20. In a prepayment electric meter, the combination with a metering mechanism and circuit, of a self-closing switch in said circuit, a cam to open said switch, a latch to maintain said switch in open position, an electric motor and circuit to operate the cam, a dial capable of rotary movement, a ratchet to give movement to said dial, a pawl-lever and a pawl pivoted on said lever to engage the ratchet, a coin-chute to guide coins paid in, a lever having its end lying in said chute, a 95 connection between said lever and an arm on the pawl, means operated by said lever to release the open switch, a contact carried by the dial and forming part of the circuit of the motor, a second contact normally in touch 100 with the first and included in the same circuit, and a connection with the metering mechanism to communicate movement to said second contact to bring it in touch with the first when the current purchased has been consumed, substantially as set forth.

110 21. In a prepayment electric meter, the combination with a metering mechanism and circuit, of a dial deriving movement from said mechanism, a multiple coin-chute having separate ways of different length for coins of different denominations, a lever having one end lying in said ways, and means operated by said lever to set the dial at points corresponding to the values of the coins paid in, substantially as set forth.

115 22. In a prepayment electric meter, the combination with a metering mechanism and circuit, of a dial capable of rotary movement, a multiple coin-chute having a plurality of 120 ways for coins of different denominations, said ways being proportioned in length to the

values of the coins paid in, a pivoted lever having its end lying in the paths of the coins traversing the chute, means operated by said lever to turn the dial, a contact on said dial 5 set by the coin-produced movements of the lever at points corresponding to the values of the coins acting on the lever, a second contact normally in touch with the contact on the dial, a connection with the metering mechanism 10 to give movement to the second contact, electrically-operated means for opening the meter-circuit, and a circuit for said devices that includes the two contacts, substantially as set forth.

15 23. In a prepayment electric meter, the combination with a metering mechanism, of means for controlling the duration of the metering action, a coin-chute having a plurality of ways to guide coins of different denominations from the point of entrance to a coin-receptacle, a lever having one end lying in the coinways of the chute, said ways having operative portions of different lengths corresponding to the values of coins traversing 20 said ways, whereby the coin-produced strokes of said lever will vary in extent in the same proportion, and means operated by said lever to set the controlling means in accordance with the variation of said strokes, substantially 25 as set forth.

24. In a prepayment electric meter, the combination with a metering mechanism and circuit, of electrically-operated devices for arresting the supply of current, a coin-chute, 30 a lever lying in said chute in the path of the coins traversing the same, a dial deriving a movement from each coin-produced movement of said lever, a circuit for the electrical devices that arrest the current-supply, two 35 contacts included in said circuit and normally in touch with each other, one of said contacts being carried by the dial, whereby said circuit is opened at the first coin-produced movement of the lever, and means operated by the metering mechanism to bring 40 said contacts in touch again and thereby establish said circuit when the current paid for 45 has been supplied, substantially as set forth.

25. In a prepayment electric meter, the combination with a metering mechanism and circuit, said mechanism including a moving armature, of a self-closing switch to start and stop the meter, means for holding said switch 50 in open position, a motor and motor-circuit 55 to open said switch, a coin-chute to guide the coins paid in to a place provided for them, a lever having its end portion lying across the path of the coins traversing said chute, a device actuated by the motor and bearing 60 against a contact on the switch to open the latter, said device and contact being included in the motor-circuit, two contacts normally 65 in touch with each other and also included in said motor-circuit, means for giving rotary movement to one of said contacts by each

coin-produced movement of the lever, and a connection with one of the gears of the registering-dials to move the other contact in the same direction and path, substantially as set forth.

70 26. In a prepayment electric meter, the combination with a metering mechanism and circuit, said mechanism including a moving armature, of a self-closing switch to start and stop the meter, a coin-chute, a lever having its end portion lying across the path of the coins traversing said chute, electrically-operated means and a circuit for the same to open the switch and thereby arrest the supply of current, two contacts forming part of the circuit of the devices for opening said switch, a dial carrying one of said contacts, means for moving said dial a fixed distance at each coin-produced movement of the lever, and means for moving the other contact in the same direction and path by the gearing of one of the registering-dials of the meter, substantially as set forth.

80 27. In a prepayment electric meter, the combination with a metering mechanism and a circuit, of a self-closing switch to initiate and arrest the supply of current, a pivoted latch to sustain said switch in open position, a lever having its end portion lying in the path of coins paid in, a chute to guide said coins 85 having a slot to guide the lever in its coin-produced movement, a device operated by said lever to trip the latch sustaining the switch, electrically-operated means and a circuit for the same to open said switch, a device operated by said means and engaging a contact on the switch, said device and contact forming part of the circuit of the means for opening the switch, two contacts also included in said circuit and normally in touch with each 90 other, means for moving one of said contacts a fixed distance by each coin-produced movement of the lever, and a connection with the gearing of one of the registering-dials to move the other contact in the same direction, whereby the circuit of the devices opening the switch is established by said contacts and broken, when the switch is opened, by the device raising said switch passing off the contact on the latter, substantially as set forth.

100 28. In a prepayment electric meter, the combination with a metering mechanism and a circuit, of a switch to initiate and arrest the supply of current, electrically-operated devices and a circuit for opening said switch, 105 two contacts in said circuit which are separated by opening the switch and brought in touch with each other by closing said switch, two contacts also included in said circuit and normally in touch with each other, coin-operated means for separating said contacts when the switch is closed, and a connection with the metering mechanism to impart movement to one of them to restore their engagement 110 and establish the circuit of the switch-open- 115

ing devices, said circuit being thus closed at one point and opened at another, substantially as set forth.

29. In a prepayment electric meter, the combination with a metering mechanism and a circuit, of a spring-closed switch, a device to open said switch, means for supporting said switch in its open position, a coin-operated lever to release the open switch, electrically-actuated means for operating the switch-opening device, and a circuit for said electrically-actuated means which is established by a con-

tact deriving movement from the metering mechanism and opened by the device that opens the switch, substantially as set forth. 15

In testimony whereof we have hereunto set our hands in presence of two subscribing witnesses.
